DESIGN FOR A DISPLAY CASE

Cyrus F. Hoffman, Trenton, N. J., assignor to C. V. Hill & Company, Inc., Trenton, N. J., a corporation of New Jersey

Application May 13, 1942, Serial No. 106,880

Term of patent 14 years

To whom it may concern:

Be it known that I, Cyrus F. Hoffman, a citizen of the United States, residing at Trenton, in the county of Mercer and State of New Jersey, have invented a new, original, and ornamental Design for a Display Case, of which the following is a specification, reference being had to the accompanying drawing forming part thereof.

Fig. 1 is a perspective view of a display case embodying my design;

Fig. 2 is a top plan view of the display case illustrated in Fig. 1; and

Fig. 3 is an end elevational view of the display case illustrated in Fig. 1.

I claim:

The ornamental design for a display case, as shown.

CYRUS F. HOFFMAN.
